DECOY FOR GUIDED MISSILES

Fred H. Rehr, San Diego, Calif.

Filed Oct. 31, 1958, Ser. No. 771,059

2 Claims. (Cl. 244—14)

This invention relates to a device for diverting a guided missile from an elevated path along which it is moving.

Such missiles are known which are launched from platforms on the ground or released from airplanes in the sky and which are steered toward a target by suitable control members mounted in them. Each missile also carries a charge of high explosive which explodes upon striking the target. When the target is an aircraft in flight, its radio or radar transmitter sends out radio waves of one or more frequencies and its hot exhaust pipe and exhaust gas emit infrared radiations. If the missile is provided with a receiver or detector which picks up these radio waves or currents or infrared rays, amplifies them and passes the information as to their direction on to the controls of the missile it can be guided to the target source of radiant energy.

It is a main purpose of my invention to provide a decoy device which remains suspended a long time high in the sky and is continually radiating waves which may be picked up by such a guided missile, divert it from the path along which it is moving, steer it towards the decoy and cause it to collide therewith and explode.

A further object is to provide such a decoy device which is continually radiating radio waves capable of controlling the radio controls of a guided missile and also infrared rays capable of operating its other controls so that the missile will be guided to the decoy irrespective of which type of wave energy its receiver picks up.

Another object is to provide a decoy of the type described with a balloon which will keep it suspended for a long time at a substantially constant elevation in the sky.

A further object is to provide a hollow casing for the decoy which will contain and enclose its component parts and is shaped as a rocket which is self propelled to a high elevation where the balloon and radiant energy source or sources are expelled from the casing and remain suspended at a desired high altitude.

Other objects will become apparent as a detailed description of my novel decoy proceeds. For a better understanding of the invention reference is made to the accompanying drawings, in which:

FIG. 1 is a diagram showing the decoy on a firing platform and at different stages after firing;

FIG. 2 is a longitudinal sectional view through the decoy some of the component parts being shown schematically;

FIG. 3 is a front view of the decoy in operative position in the sky;

FIG. 3a is an enlarged view of the decoy of FIG. 3;

FIG. 4 is a cross section on line 4—4 of FIG. 3a;

FIG. 5 is a circuit diagram of the radio transmitter and infrared lamp;

FIG. 6 is a sectional view of a tuning condenser and a schematic view of a spring motor for rotating it and;

FIG. 7 is an end view of a rotatable plate of the tuning condenser.

Referring to FIGS. 3 and 3a the decoy comprises a flexible balloon 10 which supports a hollow cylindrical casing 11 containing a radio transmitter 12, a spring motor 13, an infrared lamp 14 or other source of infrared rays and a non-directional antenna 15. The top of casing 11 is provided opposite lamp 14 with four large openings or windows 16 so that the infrared rays emitted are radiated in all directions from the sides of the casing. The top of lamp 14 is preferably coated with a reflecting coating

2

17 (FIG. 2) which prevents any substantial amount of the emitted rays from traveling up and heating the bottom of balloon 10.

Referring to FIG. 5, the transmitter illustrated comprises an oscillator tube 18 which has a tuned plate circuit 19 to which current is supplied by a battery 20 when the switch 21 is closed. Circuit 19 comprises an adjustable tuning condenser 22 and an inductance coil 23 to which is inductively coupled a feedback coil 24 in the grid circuit 25 which also includes a small battery 26 for negative grid bias. Condenser 22 (FIGS. 6 and 7) comprises a plurality of thin metal plates 27 mounted on a rotary shaft 28 supported in insulating bearings 29 carried by a metal supporting frame 30. Frame 30 has a plurality of thin metal stator plates 31 which lie closely adjacent plates 27 and are of substantially the same shape as these plates. Spring motor 13 may be of any known type which will slowly rotate shaft 28 to cause the frequency of the oscillations generated by tube 18 to increase from a minimum frequency to a maximum frequency at each revolution of shaft 28. The range of radio frequencies through which the oscillator is tuned includes the frequency or frequencies to which the resonant radio receiving or input circuits of the guided missiles to be captured are tuned. The oscillations generated by oscillator tube 18 are amplified by amplifier tube 32 whose output circuit is coupled by transformer 33 and lead 34 to antenna 15. Preferably battery 20 is also used to supply heating current to lamp 14 through the circuit shown which includes an adjustable resistor 35 which regulates the amount of heating current supplied. A suitable filter such as choke coil 36 and condenser 37 prevents the radio frequency currents in the plate circuit of amplifier 32 from passing through battery 20 and lamp 14.

35 Casing 11 (see FIG. 3a) terminates at its upper end in a cylindrical portion 38 whose upper end tapers out to provide a seat 39 for a ball check valve 40. The cylindrical lower end 41 of the balloon fits around casing portion 38 and is secured thereto by cord or wire wrapping 42. One or more holes 43 are made through casing portion 38 for a purpose to be described. Valve 40 is biased against seat 39 by spring 44 and a flexible wire or cord 45 connects valve 40 to the top 46 of the balloon as shown. The balloon is filled with hydrogen or helium in a manner to be later described and distends as it rises. When it reaches a certain height, its small ascent above this level would cause its further distention which would cause wire 45 to lift valve 40 from its seat 39, permitting some of its contained gas to escape through the openings 43 and restore the balloon to its desired maximum size. Means is thus provided to keep the balloon for a long time approximately at a desired height.

To propel the decoy high into the sky, its component parts are stowed in a rocket (see FIG. 2) comprising a generally cylindrical metal casing 47 having the usual guide fins 48. The rear end of the casing contains a charge of solid propellant fuel 49 which can be ignited by any suitable igniter 50. A metal barrier 51 extends across the casing and is secured thereto as by welding, the center of the barrier supporting a short fuse 52 adapted to ignite a power charge 53. A circular plate 54 separates the powder from the rear or lower end 55 of casing 11. Member 55 carries an insulating bushing 56 within which antenna 15 is slidably, the top end of the antenna having a stop flange 57 adapted to engage bushing 56 and limit the outward motion of the antenna under the bias of spring 58 after the decoy leaves casing 47 as later described. A cylindrical casing 59 extends along the inner face of casing 47, this casing being composed of 6 or more separate segments made of polymerized resin, the sides of each segment abutting the sides of the two

adjacent segments so that casing 59 can easily fall apart after it leaves casing 47. The top end of casing 59 is provided with a groove 60 which receives an expandable snap ring 61 which retains a circular plastic disc 62 in position, this disc having a concave face against which the top portion of balloon 10 presses, as illustrated. Disc 62 has a suitable opening 63 to provide access to any known type of filler or check valve 64 to which a hose may be connected to fill the balloon with gas under pressure. A detachable pointed nose piece 65 fits against the ends of casings 47 and 59 and minimizes the air resistance as the rocket rises quickly to altitude. The movable blade of switch 21 carries a button 66 which protrudes through a small opening in casing 11 and rests against plastic casing 59 to retain the switch in open position before the rocket is fired. A spring 67 biases the switch blade toward closed position.

To launch the decoy into the sky in a locality where enemy guided missiles are expected, before nose cap 65 is applied, balloon 10 is filled with hydrogen or helium gas to the desired pressure through valve 64. Cap 65 is then attached and the rocket put on a launching platform 68 (FIG. 1) and fired by operating igniter 50. The thrust developed by the burning of fuel charge 49 propels the rocket to a high altitude where the burning of fuse 52 and consequent firing of powder charge 53 causes casings 11 and 59 to be expelled from casing 47. The various segments composing casing 47 separate due to the outward pressure of the balloon on them and the balloon soon distends to its normal size and shape as seen in FIG. 3. The separation of the segments of casing 59 permits button 66 to move out under the bias of spring 67 and thus close switch 21. Current from battery 20 soon renders oscillator 18 and amplifier 32 operative and since antenna 15 is now projecting below the bottom 55 of casing 11, as shown in FIGS. 3 and 3a, radio waves are transmitted in all directions from the antenna and also infrared radiations are propagated in all directions outwardly from lamp 14, as shown in FIG. 3. As above explained the frequency of the radio waves transmitted is slowly varied through a range of frequencies so that a guided missile controlled by a radio receiver whose resonant circuit or circuits are tuned to any frequency within the band of frequencies transmitted by the decoy will be diverted from the path along which it is moving and steered toward the decoy until it collides with it. On the other hand if the missile has steering controls operated by a receiver sensitive to infrared radiations, it will be diverted from its path, guided to the decoy and destroyed. The decoy will remain in the sky in the position shown in FIG. 3 for a long time until the spring motor 13 runs down or the battery 20 becomes exhausted. Instead of spring motor 13, an electric motor operated by current from battery 20 could be used to rotate a gear reducer (not shown) which rotates shaft 28 slowly.

This invention may be embodied in other forms or carried out in other ways without departing from the spirit or essential characteristics thereof. The present embodiment of the invention is therefore to be considered as in all respects illustrative and not restrictive, the scope of the invention being indicated by the appended claims, and all changes which come within the meaning and range of equivalency of the claims are intended to be embraced therein.

Having thus described my invention, what I claim as new and useful and desire to secure by Letters Patent is:

1. A device for diverting a guided missile from a path along which it is moving in response to electromagnetic waves picked up thereby from a target comprising: an inflated balloon; a casing depending from said balloon said casing having a wall provided with a plurality of oppositely disposed openings of large area therein; and a continuous source of electromagnetic waves of intensity comparable to those emitted by said target disposed within said casing, said source comprising a battery and an infrared lamp energized from said battery and mounted within said casing opposite said openings for emitting and radiating infrared rays through said openings in substantially all directions from the sides of said casing.

2. A decoy for diverting a guided missile from an elevated path along which it is moving comprising: a hollow casing having a detachable cap at its upper end; rocket means having a charge of solid propellant fuel and an igniter therefor associated with said casing for propelling it to a predetermined high altitude from a launching station when the igniter is ignited and the charge is fired; a housing disposed within said casing and comprising a plurality of separable members, a balloon disposed and confined within said housing and having a quantity of gas under pressure therein; means connected to said balloon and adapted to be supported thereby for radiating signals for guiding a guided missile to said decoy, said radiating means being disposed within said housing, means operable in time delayed relation to the launching of said decoy for ejecting said cap and said separable housing from said casing thereby to release said balloon and said radiating means from the housing and to distend the balloon as said members separate in response to the pressure of the balloon thereon, and valve means disposed within said balloon and responsive to a predetermined distention thereof in excess of that obtainable at said predetermined altitude for effecting partial deflation of the balloon sufficient to maintain the same at said predetermined altitude, said ejecting means comprising a powder charge and a fuse for firing the same disposed within said solid charge remotely from said igniter therefor.
